UNITED STATES PATENT OFFICE.

HIPPOLYTE MAUGRAS, OF MARSEILLE, FRANCE.

VENTILATOR.

1,133,304.

Specification of Letters Patent. Patented Mar. 30, 1915.

Application filed August 25, 1913. Serial No. 786,432.

To all whom it may concern:

Be it known that I, HIPPOLYTE MAUGRAS, citizen of France, residing at Marseille, have invented new and useful Improvements 5 in Ventilators, of which the following is a specification.

The object of the invention consists in a fan or turbine, the blades of which are enclosed in a casing which has an opening on 10 one side for exhaustion, and, on the other side, is provided with a helicoidal partition which takes up the air and conducts it into a carbureter for the production of carbureted gas.

15 On the annexed drawings: Figure 1 represents an application of the invention to a gas heater. Fig. 2 is a view of the interior face in front of the casing, carrying a helicoidal partition, finally Fig. 3 represents the 20 other half of the casing seen from the interior of the fan.

25 Referring to the drawing the device A comprises an electric fan of the usual type consisting of an electric motor B and fan blades C. The device comprises further a casing consisting of two parts E and F, the part E being removable. The part F which incloses the blades C is provided with air 30 inlet holes G. The part E, which is positioned in front of the blades C is provided with an air outlet and with a helicoidal partition forming a passage for conducting the air from the interior of the casing to the outlet. The air is led from the outlet by a pipe 35 K to the carbureter H. When the part E of the casing is removed the fan may be used for ventilation purposes in the usual manner.

The arrangement shown in the annexed drawings illustrates one application only of 40 the invention which can be used in a variety of ways without any change in the general idea.

I claim:

1. In a device of the class described, in 45 combination, a casing consisting of two parts, fan blades rotatably mounted in one of said parts, said part being provided with an air inlet, the other of said parts being provided with an air outlet and with a partition forming a passage communicating with said outlet, said second mentioned part being removable from said first mentioned part.

2. In a device of the class described, in 55 combination, an electric fan consisting of a motor and fan blades, and a two part casing, one of said parts inclosing said blades and being provided with an air inlet, the other of said parts being provided with an air 60 outlet and with a partition forming a passage communicating with said outlet, said second mentioned part being removable from said first mentioned part whereby said fan 65 may be used for the ventilation of apartments in the usual manner.

In testimony whereof I have signed my name to this specification in the presence of two subscribing witnesses.

HIPPOLYTE MAUGRAS.

Witnesses:

E. DIMEETTON,
PAUL H. CRAM.
